UNITED STATES PATENT OFFICE.

JESSE E. HANCOCK, OF DUPONT, GEORGIA, ASSIGNOR OF FIVE PER CENT TO F. B. BULLARD, OF DUPONT, GEORGIA.

SHAKING AND DUMPING GRATE.

Application filed September 23, 1922. Serial No. 590,088.

To all whom it may concern:

Be it known that I, JESSE E. HANCOCK, a citizen of the United States, residing at Dupont, in the county of Clinch and State 5 of Georgia, have invented certain new and useful Improvements in Shaking and Dumping Grates, of which the following is a specification.

This invention relates to grates and has 10 special reference to a dumping and shaking grate.

In many cases, especially in commercial adaptations such as for locomotive boilers and boilers in power and steam plants, it 15 is necessary at times to quickly dump the fire. For instance, in locomotive practice it sometimes happens that water in the boiler becomes low and the injector fails to operate. Under such conditions there is 20 great danger of burning the crown sheet of the fire box and it is advisable under such conditions to quickly dump the fire. Also in some steam plants at the end of operations it is found advisable to dump the fire.

25 One important object of the invention is to improve the general construction of dumping grates so that the fire may be dumped without any loss of time and thereby accidents may be prevented.

30 In other instances, it is desirable, especially in cleaning a fire, to be able to dump a portion of the fire without putting out the remainder.

A second important object of the invention 35 is to provide an improved dumping grate wherein construction is such that one half of the fire or ashes above the grate may be dumped while the remaining part of the fire is kept on its half of the grate.

40 Practice has also shown that the great length necessary in the grate bars under modern locomotives and like places, these bars being unsupported in the middle tends to rapid deterioration and burning out under 45 conditions of use.

A third important object of the invention is to provide an improved form of grate wherein short grate bars may be used and wherein the center of the fire will be

50 strongly supported by permanent frame beams, so that sagging of this part of the grate will be obviated.

A fourth important object of the invention is to provide an improved form of

dumping grate wherein different parts of 55 the grate may be independently dumped and wherein each part will consist of a plurality of sections which may be independently shaken.

With the above and other objects in view 60 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:—

Figure 1 is a plan view of a grate constructed in accordance with this invention, certain of the parts of the grate being broken away and omitted, and the floor, or working platform being also omitted. 70

Figure 2 is a section on the line 2—2 of 75 Figure 1.

Figure 3 is a section on the line 3—3 of Figure 1.

Figure 4 is a section on the line 4—4 of Figure 1. 80

Figure 5 is a plan view of the working end of the grate showing the floor.

Figure 6 is a detail perspective showing the end of one of the shaking rods.

Figure 7 is a detail view showing one of 85 the bearings for the rock shafts used here- with in dumping the grate portions.

In the present embodiment of the invention it has not been deemed necessary to show anything but the parts of the grate 90 itself, the same being applicable to any type of boiler. This grate consists of a main frame 10 having a longitudinally extending brace bar 11 which connects the two ends of the main frame at their center point, and a transversely extending brace bar 12. By this means the longitudinal bar divides the grate into right and left hand halves while the transverse bar divides the grate into a pair of sections in each half. 100

It is obvious that there may be as many of these sections as desirable, it being merely necessary to put in additional brace bars. Beneath the grate there are provided, centrally of each half, longitudinally aligned

105 bearing boxes 13 in each set of which there is supported a rock shaft 14 which is square between the bearings. On these rock shafts

14 are supported grate bar supporting frames 15 wherein are rockingly mounted the grate bars 16. Each of these grate bars 16 has a downwardly extending finger 17 and the fingers of each section are pivotally connected to a link 18 so that forward or backward movement of any of the links will rock the grate bars of that particular section and thus shake the grate. At the 10 front of the grate there is provided a floor 19. On each of the rock shafts is a rock arm 20 to which is pivotally connected a link 21, the other end of the link being connected to the lower end of an operating lever 22 which projects upwardly through a suitable slot 23 in the floor, hinged dogs 24 being positioned adjacent these slots so that they can be thrown down and lock the operating levers in place. By means of these 15 two operating levers either side may be rocked at will so that in case it is desired to clean one side of the fire the live coal may be raked from that side onto the other side and the ashes and cinders dumped from the side to be cleaned. The fire may be 20 then spread into the other side and similarly treated. Thus, without dumping the entire fire all of the ashes and cinders on either side may be gotten rid of. Also in an emergency both sides may be dumped at once thus getting rid of the entire fire. It will be noted that in the rock arms and operating levers just mentioned, as well as those to be mentioned hereinafter, the ends are 25 so arranged that the positions of the links may be adjusted to obtain a greater or less throw as desired. Connected to each of the grate bar links 18 is a long link 25 and supported above the floor are certain U-shaped brackets 26 in which are pivotally mounted shaker levers 27 to the lower ends of which the remaining ends of the links 25 are connected. It will be observed that 30 these shaker levers have certain offset portions to enable them to move around the boiler legs. Also it will be observed that the links 25 are pivotally mounted in the shaker levers and the pivot mount sufficiently loose to permit free movement of 35 these levers. In order to stop too great movement of the auxiliary or grate bar frames 15 there is provided on the main frame 10 certain stops 30. From the foregoing it will be seen that either half of 40 the grate may be dumped at will or any section shaken independently of the remaining section.

There has thus been provided a simple and efficient device of the kind described and for the purpose specified.

It is obvious that minor changes may be made in the form and construction of the invention without departing from the material spirit thereof. It is not, therefore, desired to confine the invention to the exact

form herein shown and described, but it is desired to include all such as properly come within the scope claimed.

Having thus described the invention what is claimed as new, is:—

1. In a grate of the class described, a main frame, a brace beam extending longitudinally of the main frame at its center and dividing the main frame into halves, other brace beams extending transversely of the main frame and dividing the respective halves into a plurality of sections, a rock shaft extending longitudinally of the main frame beneath each half and journaled to the main frame, grate bar supporting frames fitting in said sections of the main frame and each fixedly mounted on a respective rock shaft, grate bars rockingly supported in the bar supporting frames, rock arms fixed on the respective rock shafts and constituting operating levers whereby to oscillate the rock shafts and tilt the bar supporting frames, means adjacent the main frame in alinement with the longitudinal brace beam to operate said rock arms, and independent means separate from the rock shaft oscillating mechanism and located adjacent the ends of the respective halves and centrally disposed with relation to said respective halves for rocking the bars of the respective sections.

2. In a grate of the class described, a main frame, a brace beam extending longitudinally of the main frame at its center and dividing the main frame into halves, other brace means extending transversely of the main frame and dividing the respective halves into a plurality of sections, a rock shaft extending longitudinally of the main frame beneath each half and journaled to the main frame, grate bar supporting frames fitting in said sections of the main frame and each fixedly mounted on a respective rock shaft, grate bars rockingly supported in the bar supporting frames, rock arms fixed on the respective rock shafts and constituting operating levers whereby to oscillate the rock shafts and tilt the bar supporting frames, a pair of operating levers located in alinement with the front end of the brace beam and pivoted intermediate their ends, links each connecting one of the operating levers to a respective rock arm, and means separate from the mechanism for oscillating the rock shaft to rock the grate bars of the sections independently.

3. In a grate of the class described, a main frame, a brace beam extending longitudinally of the main frame at its center and dividing the main frame into halves, other brace beams extending transversely of the main frame and dividing the respective halves into a plurality of sections, a rock shaft extending longitudinally of

the main frame beneath each half and journaled to the main frame, grate bar supporting frames fitting in said sections of the main frame and each fixedly mounted 5 on a respective rock shaft, grate bars rockingly supported in the bar supporting frames, rock arms fixed on the respective rock shafts and constituting operating levers whereby to oscillate the rock shafts and tilt 10 the bar supporting frames, a pair of operating levers located in alinement with the front end of the brace beam and pivoted intermediate their ends, links each connecting one of the operating levers to a respective 15 rock arm, means separate from the mechanism for oscillating the rock shaft to rock the grate bars of the sections inde-

pendently comprising a shaker lever for each grate section located at the front of and substantially in central alinement with the 20 respective grate section, arms projecting downwardly from the respective grate bars, bars each pivotally connected to all of the arms of a respective section, and links each rotatably journalled at one end in the lower 25 end of a respective shaker lever and pivotally connected at the other end to one of the last mentioned bars, said journal connections being sufficiently free to permit shaking movement of the shaking levers. 30

In testimony whereof I affix my signature.

JESSE E. HANCOCK.
